United States Patent Office

Des. 181,735

Patented Dec. 17, 1957

181,735

COMPOSITION FLOOR COVERING OR THE LIKE

Thomas M. Knowland, Belmont, Mass., assignor, by
mesne assignments, to American Biltrite Rubber Co.,
Inc., a corporation of Delaware

Application January 5, 1956, Serial No. 39,609

Term of patent 14 years

(Cl. D92—4)

The figure is a plan view of a composition floor covering or the like, showing my new design. The solid lines on the figure outline a design unit which is repeated in regular succession as indicated by extensions beyond the unit boundaries.

The characteristic feature of this invention is a series of leaflike figures of similar shape spaced in a generally random fashion on a floor covering, the surface of such figures being formed by a number of small daubs which give a special effect such as a tapestry, all as shown.

I claim:

The ornamental design for a composition floor covering or the like, substantially as shown and described.
